UNITED STATES PATENT OFFICE.

PARRY D. SAYLOR, OF BUFFALO, NEW YORK.

DESIGN FOR A VEHICLE TIRE TREAD.

61,351.

Specification for Design.

Patented Aug. 8, 1922.

Application filed August 20, 1921. Serial No. 493,988. Term of patent 3½ years.

To all whom it may concern:

Be it known that I, PARRY D. SAYLOR, a citizen of Great Britain, residing at 124 Jewett Parkway, in the city of Buffalo, county of Erie, and State of New York, have invented a new, original, and ornamental Design for Vehicle Tire Treads, of which the following is a specification, reference being had to the accompanying drawing, forming part thereof.

Fig. 1 is a fragmentary view of the tire tread.

Fig. 2 is a cross section of Fig. 1 on the line 2—2.

It will be understood that although I have illustrated the design of tire tread only as it may be embodied in a pneumatic vehicle tire, the design is applicable to and is intended to be used in connection with vehicle tires regardless of whether they are pneumatic, solid or cushion in type.

I claim:

The ornamental design for a vehicle tire tread as shown.

PARRY D. SAYLOR.
